US0D1054925S

(12) **United States Design Patent** (10) **Patent No.:** **US D1,054,925 S**
Hu (45) **Date of Patent:** **** Dec. 24, 2024**

(54) **BICYCLE**

(71) Applicant: **SHENZHEN COSWHEEL TECHNOLOGY CO., LTD.**, Shenzhen (CN)

(72) Inventor: **Ding Hu**, Shenzhen (CN)

(**) Term: **15 Years**

(21) Appl. No.: **29/897,270**

(22) Filed: **Jul. 13, 2023**

(51) **LOC (14) Cl.** **12-11**

(52) **U.S. Cl.**

USPC **D12/111**; D12/110

(58) **Field of Classification Search**

USPC D12/110, 111, 114, 115, 117; D21/412, D21/414, 419, 423, 425, 426, 427, 431, D21/432

(57) **CLAIM**

The ornamental design for a bicycle as shown and described.

DESCRIPTION

FIG. 1 is a perspective view of bicycle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2.

The dot-dash broken lines represent boundaries of the enlarged portions and form no part of the claimed design.

1 Claim, 10 Drawing Sheets
